UNITED STATES PATENT OFFICE

JENNINGS HOOD, OF LANSDOWNE, PENNSYLVANIA

DESIGN FOR A TOBY JUG

Application filed October 8, 1928. Serial No. 28,408. Term of patent 7 years.

To all whom it may concern:

Be it known that I, JENNINGS HOOD, a citizen of the United States, residing in Lansdowne, in the county of Delaware and State of Pennsylvania, have invented a new, original, and ornamental Design for a Toby Jug, of which the following is a specification, reference being had to the accompanying drawing, forming part hereof, in which—

Fig. 1 is a view in side elevation, Fig. 2 is a

view in front perspective, and Fig. 3 is a view in rear elevation.

I claim:

The ornamental design for a toby-jug, substantially as shown.

In testimony whereof I have hereunto signed my name this 29th day of September, A. D., 1928.

JENNINGS HOOD.
